UNITED STATES PATENT OFFICE.

HENRY G. RUNNE, OF ROCHESTER, NEW YORK, ASSIGNOR OF ONE-HALF TO CHARLES L. TOWNSEND, OF ROCHESTER, NEW YORK.

FOLDING CLOTHESRACK.

1,399,156.

Specification of Letters Patent.

Patented Dec. 6, 1921.

Application filed April 25, 1919. Serial No. 292,528.

To all whom it may concern:

Be it known that I, HENRY G. RUNNE, of Rochester, in the county of Monroe and State of New York, have invented certain 5 new and useful Improvements in Folding Clothesracks; and I do hereby declare the following to be a full, clear, and exact description of the same, reference being had to the accompanying drawings, forming a 10 part of this specification, and to the reference-numerals marked thereon.

My present invention relates to supports and more particularly to garment racks or hangers and it has for its object to provide 15 a simple, cheap and convenient device of this nature for general use but adapted more particularly for use in closets and hallways and other places where the operating space is limited. The invention contem- 20 plates provision for the accommodation of a relatively large number of articles of clothing in such a way that they are readily accessible but are held flat against the wall or other support in a manner to be pro- 25 tected and prevented from wrinkling. To these and other ends the invention resides in certain improvements and combinations of parts all as will be hereinafter more fully described, the novel features being pointed 30 out in the claims at the end of the specifica- tion.

In the drawings:

Figure 1 is a front view of a folding clothes rack constructed in accordance with 35 and illustrating one embodiment of my invention, the protective curtain being in position;

Fig. 2 is a similar view with the protective curtain removed;

Fig. 3 is an enlarged side view in vertical section through the curtain, and

Fig. 4 is a top view, enlarged, with the curtain removed and the arms in raised position, portions of the curtain rod being 45 broken away.

Similar reference numerals throughout the several views indicate the same parts.

In the embodiment shown, the parts are supported on a base board or block 1 that 50 may be screwed to a wall but which is also provided at the top with an enlarged eye 2 adapting it to be hung upon an ordinary closet hook. Secured to this block, as by the screws 3 extending through its intermediate portion, is a yoke shaped sheet metal

bracket 4 forming a pair of forwardly projecting spaced plates 5. Between these plates in an inclined row are pivoted at 6 a plurality of arms 7, 8, 9, 10 and 11 adapt- 60 ed to swing vertically in the same plane. These arms are of progressively increasing length, the inner one 11 being the shorter and the outer one 7 the longer and at the end of each is a hook or similar means 12 for the attachment of a garment hanger 13 65 that may be of the usual form. On the intermediate arms, the hooks are located on the portions that project beyond the ends of the under arms of shorter length so that these hooks are readily accessible but do not 70 increase the space ordinarily occupied, collectively, by the arms themselves.

The arms normally hang folded in the positions of Figs. 1, 2 and 3 and, as shown in Fig. 3, the garment hangers 13 then hang 75 vertically in parallelism to each other and to the plane of the wall. If they carry clothing, the garments hang naturally but flat against each other and if they be bulky, they will simply tend to expand the group of 80 arms and prevent them from folding as flat together as they otherwise would. To remove the garment hanger or obtain access to particular articles of clothing on any one arm, the arms are swung upwardly to the 85 dotted line positions of Fig. 3 in which positions, the hooks 12 automatically separate because of the character of the pivotal ar- 90 rangements and greater freedom is offered in manipulating the hanger or hangers se- selected.

I provide means connecting the arms together for joint movement. It is convenient to manipulate all of the arms through the medium of the outermost arm 7 and to this 95 end, I employ in the present instance, a link 14 pivoted at 15 to said outermost arm and at 16 to the innermost arm 11. At properly spaced intermediate points, the link is pro- 100 vided with lateral extensions 17 lying be- tween the intermediate arms so that the latter are lifted or depressed according to the movement of the outermost arm 7. A link 14 may be provided upon each side of the arms, in which case the extensions 17 105 may be constituted by bars connecting these link members.

I also provide means for temporarily re- 110 taining the arms in their raised positions. As they are all connected the locking of one

is sufficient, so in the present instance, I provide a notch 18 in the outermost arm 7 which is automatically engaged by a gravity latch 19 on the support 1 when the arms are raised 5 to the dotted line position of Fig. 3. The latch 19 may consist, as best shown in Fig. 4, of a wire bail having its ends pivoted at 20 in bearings bored laterally in the base board 1.

10 There is a similarly mounted bail 21 held horizontally in the block 1 and of a lateral spread sufficient to include the extreme lateral range of the hangers 13. This bail is run through the hem of a curtain 22 which it 15 supports and the curtain hangs over the arms and the garments supported thereby and protects them from dust, as shown in Figs. 1 and 3.

I claim is my invention:

20 1. In a folding clothes rack, the combination with a base board or support, of a plurality of arms pivoted thereto in different vertical planes for vertical swinging movement in the same plane, each arm being provided with means for attaching a garment hanger thereto, and means connecting the arms for joint movement.

25 2. In a folding clothes rack, the combination with a base board or support, of a plurality of arms pivoted thereto for vertical swinging movement in the same plane, each arm being provided with means for attaching a garment hanger thereto and a link pivoted to the upper and lower arms and having 30 extensions lying between intermediate arms whereby all of the arms are connected for 35 joint movement.

3. In a folding clothes rack, the combination with a base board or support, of a plurality of arms of progressively increasing 40 length pivoted thereto for vertical swinging movement in the same plane to and from a depending and extended position, each arm being provided with means for attaching a 45 garment hanger thereto and the arm pivoted lowermost being the shortest, a link connecting all of the arms for joint movement and a latch coöperating with the uppermost

arm to maintain it and all of the arms in raised or extended position.

4. In a folding clothes rack, the combination with a base board or support and a yoke shaped bracket secured thereto and forming a pair of forwardly projecting spaced plates, of a plurality of arms of progressively increasing length pivoted in different vertical planes between the plates for vertical swinging movement in the same plane with each other, each arm being provided at its extremity with means for the attachment of a garment hanger.

5. In a folding clothes rack, the combination with a base board or support and a yoke shaped bracket secured thereto and forming a pair of forwardly projecting spaced plates, 65 of a plurality of arms of progressively increasing length pivoted between the plates for vertical swinging movement in the same plane with each other, each arm being provided at its extremity with means for the attachment of a garment hanger, means connecting the arms together for joint movement and a latch arranged to swing above the arms and to coöperate with the uppermost one to maintain all of the arms in raised 75 position.

6. In a folding clothes rack, the combination with a base board or support of a plurality of arms of progressively increasing length pivoted thereto in different horizontal and vertical planes for vertical swinging movement in the same plane, each provided with means for attaching a garment hanger thereto, the arm pivoted lowermost being the shortest, a connecting link pivoted to the 85 upper and lower arms and coöperating with the intermediate arms whereby all of said arms are connected for joint movement, a latch engaging means on the uppermost pivoted arm, a latch pivoted to said base board 90 above said uppermost pivoted arm and adapted to coöperate with said latch engaging means on said arm to hold all of said arms in a substantially horizontal or raised position.

HENRY G. RUNNE.
